UNITED STATES PATENT OFFICE.

JOHN KIRSCHBAUM, OF WATERBURY, CONNECTICUT, ASSIGNOR, BY MESNE
ASSIGNMENTS, TO THE CHASE COMPANIES, INCORPORATED, OF WATERBURY,
CONNECTICUT.

CURTAIN-FASTENER.

1,304,489.

Specification of Letters Patent. Patented May 20, 1919.

Application filed January 9, 1919. Serial No. 270,386.

To all whom it may concern:

Be it known that I, JOHN KIRSCHBAUM, a citizen of the United States, residing at Waterbury, in the county of New Haven and State of Connecticut, have invented a new and useful Improvement in Curtain-Fasteners; and I do hereby declare the following, when taken in connection with the accompanying drawings and the characters of reference marked thereon, to be a full, clear, and exact description of the same, and which said drawings constitute part of this application, and represent, in—

Figure 1 a view in side elevation of a curtain-fastener constructed in accordance with my invention, and shown as applied to a section of a curtain.

Fig. 2 a plan view thereof.

Fig. 3 a reverse plan view thereof.

Fig. 4 a view in vertical longitudinal section on the line 4—4 of Fig. 2.

Fig. 5 a detached plan view of the spring-carrying plate showing the locking-spring as mounted upon it.

Fig. 6 a detached view in side elevation of the post-member of the fastener.

My invention relates to an improved curtain-fastener particularly designed for use in fastening the curtains of automobiles, but adapted to be used in a variety of kindred situations, the object being to produce a compact, reliable and durable device of neat and attractive workmanship, convenient and easy to operate, and having the exposed surface of its button-member closed so as to exclude moisture and to prevent objects from being caught upon it.

With these ends in view, my invention consists in a curtain-fastener having certain details of construction as will be herein-after described and pointed out in the claims.

In carrying out my invention as herein shown, I employ an oblong outer plate or housing 5 having rounded sides and straight parallel ends and formed midway of its length and at a right angle to its major axis with a raised hollow oval boss 6. The sides and ends of the said plate are formed with a continuous depending flange 7 which gives it the character of a housing. The side reaches of the said flange 7 are formed with integral depending assembling-prongs 8, and the end

reaches thereof with shorter assembling-prongs 9.

This outer plate or housing 5 is imposed upon a spring-carrying plate 10 upon the outer surface of which the edge of its flange 7 rests, the plate 10 being of the same general outline as the plate or housing 5, but larger. The prongs 8 aforesaid pass through slots 11 arranged near the rounded sides of the plate 10, while the prongs 9 pass through slots 12 located near the ends thereof and are turned inward upon its lower face, whereby the two plates are fastened together. The said plate 10 is also formed with a centrally arranged oval clearance-opening 13 having its major axis at a right angle to the major axis of the plate and registering with the oval entrance into the boss 6. Upon the plate 10 I mount a wire locking-spring composed of two parallel complementary arms 14 and a loop 15 the ends of which latter offset beyond the respective arms which cross the ends of the opening 13 at a right angle thereto as clearly shown in Fig. 5, and also stand across the ends of the entrance into the boss 6 in the same relation thereto as to the said opening 13. The locking-spring although mounted upon the plate 10, is really located within the housing 5, as shown in Fig. 4. For preventing the lateral displacement of the spring and positioning it upon the plate 10, the same is formed with two pairs of upstanding struck-up lugs 16 the respective pairs of which are located on opposite sides of the opening 13 and spaced apart so as to fall between the arms 14 of the spring. The plate is also formed with an upstanding positioning lug 17 which enters one of the offsetting ends of the loop 15 of the spring, as shown in Fig. 5. The spring having been mounted upon the plate 10, the said plate and housing are clamped together by the prongs 9 as described, and thereafter the said housing and plate are handled as one unitary part.

The housing 5 and spring-carrying plate 10 as thus fastened together and forming a unitary part, are clamped upon the curtain 18 whether the same is of fabric, leather or other material, by means of an inner or assembling-plate 19 substantially corresponding in outline to the plate 10 and formed

with slots 20 for the reception of the assembling-prongs 8, which, after passing through the slots 11 in the plate 10, pass through self-punctured openings in the curtain 18 and then through the said slots 20 in the plate 19 upon the lower face of which they are turned inward as shown in Fig. 3, whereby the curtain is clamped between the plates 10 and 19. The turned over prongs 9 of the housing 5 force portions of the curtain into holes 21 in the plate 19, as shown in Fig. 4, and so more firmly clench the curtain and assist in preventing the button-member of the fastener from being shifted 15 in position upon it. The plate 19 is also formed with a centrally arranged oval opening 22 having its major axis at a right angle to the major axis of the plate 19 and registering with the oval opening 13 in the 20 plate 10 and with the oval entrance into the interior of the boss 6. The plate 10 is by preference and as shown, struck downward around its opening 13 to form a bearing edge 23, as shown in Fig. 4. The parts 25 above described, when mounted upon the curtain, form the button-member of the fastener.

With such button-member I employ a one-piece post-member or stud, comprising 30 a conical head 25, a well defined annular channel 26 below the same, a shank 27, a nut 28 and a threaded stem 29, the channel 26 being adapted in size to receive those portions of the arms 14 of the spring which 35 cross the oval openings 13 and 22 and the oval entrance into the boss 6. The upper edge of the channel 26 forms a sharp guard-shoulder 30 the function of which will be hereinafter described.

40 When the button-member of my improved fastener is pressed over the post-member thereof, the conical head 25 of the same temporarily spreads the spring arms 14 apart to permit the head 25 to enter the 45 interior of the boss 6, after which they spring into the channel 26 at opposite points thereof and lock the button-member to the post-member of the fastener at two opposite points, so that the operation of "buttoning 50 the curtain" is effected by simply pressing the button-member upon the post-member until the arms of the spring have been entered into the channel of the post. To "unbutton the curtain", it is pulled in either 55 direction in line with the major axis of the oval boss 6 of the housing, against the tension of either arm 14 of the spring the other arm 14 of which is by this movement caused to move out of that portion of the channel 60 26 in the post in which it is located. The button-member is now tilted or raised with respect to the post-member to cause the disengaged arm of the spring to ride over the conical head of the post, the button-member 65 at this time rocking, as it were, upon the

engaged arm of the spring as upon a pivot until the button-member has been entirely disengaged from the post-member. This is a very easy and simple movement and rendered doubly convenient from the fact that 70 the curtain may be pulled in either direction for the removal of the button-member from the post-member in this manner. However, the sharp outer shoulder 30 of the channel 26 stands on constant guard to prevent either arm 14 of the spring from riding out of the recess in case the button-member of the fastener is tilted with respect to the post-member thereof prior to being pulled in one direction or the other in 80 line with the major axis of the boss 6 and substantially in a plane at a right angle to the axis of the post-member. It follows that even if any strain upon the curtain should act to pull the button-member, as described, with respect to the post-member, the former would still be held in engagement with the latter by the engagement of one arm of the spring with the shoulder of the recess, inasmuch as the unbuttoning of 85 the fastener requires two distinct movements; namely, a longitudinal movement and a rocking or tilting movement.

I claim:—

1. In a curtain-fastener, the combination 95 with a post-member having an annular recess the outer edge of which forms a guard-shoulder, of a button-member having an oblong opening for the reception of the said post-member, and a locking-spring comprising 100 two arms adapted to enter opposite points in the said recess in the post-member and normally standing across the ends of the said oblong opening of the button-member at a right angle to the major axis thereof, 105 whereby the pulling of the button-member in one direction or the other in line with the major axis of the said oblong opening and substantially at a right angle to the axis of the said post-member for disengaging one or 110 the other of the said arms from the said guard-shoulder, is a condition precedent to the removal of the button-member from the post-member.

2. In a curtain-fastener, the combination 115 with a post-member having an annular recess the outer edge of which forms a guard-shoulder, of a button-member comprising a housing having an oval boss for the reception of the head of the said post, and a 120 locking-spring comprising two arms adapted to enter portions of the said annular recess and normally standing across the ends of the entrance to the said boss at a right angle to the major axis thereof, whereby 125 when the button-member is pulled in one direction or the other in line with the said boss and at substantially a right angle to the axis of the post-member and tilted, one or the other of the said arms of the spring 130

is disengaged from the said guard-shoulder and permits the button-member and post-member to be separated.

3. In a curtain-fastener, the combination 5 with a post-member having an annular recess the outer edge of which forms a guard-shoulder, of a button-member comprising an outer plate or housing having an oval boss standing at a right angle to its major 10 axis, and a spring comprising two arms normally standing across the ends of the entrance into the said boss at a right angle to the major axis thereof and forcibly separated by the head on the post-member to 15 permit the said head to enter the said boss in which it is retained by the entrance of the said arms into the said recess, whereby the pulling of the button-member in one direction or the other in line with the major 20 axis of the said oblong opening and substantially at a right angle to the axis of the said post-member for disengaging one or the other of the said arms from the said guard-shoulder, is a condition precedent to the 25 removal of the button-member from the post-member.

4. In a curtain-fastener, the combination with a post-member having an annular recess, of a button-member comprising a housing having an oval boss, a spring-carrying plate to which the said housing is fastened and which has a clearance-opening registering with the oval entrance into the said boss, and a spring mounted upon the said 30 plate and having two arms normally standing across the ends of the entrance into the said boss at a right angle to the major axis thereof; and an assembling-plate to which the housing is secured, the curtain being interposed between the spring-carrying plate and the said assembling-plate.

5. In a curtain-fastener, the combination with a post-member having an annular recess, of a button-member comprising an outer 45 plate or housing and a spring-carrying plate, the former having an oval boss and a depending flange furnished with prongs, and the latter having a clearance-opening registering with the entrance to the said boss, 50 and with slots for the reception of the said prongs by which the said housing and plate are fastened together to form a unitary part, a spring interposed between the said hous-

ing and plate and having two arms normally extending across the entrance into the said 55 boss at a right angle to the major axis thereof, and adapted to enter the recess in the head, and an assembling-plate having an opening for the passage of the post-member and adapted to receive prongs of the said 60 housing, whereby the button-member of the fastener is mounted upon the curtain which is clamped between the spring-carrying plate and the assembling-plate.

6. In a curtain fastener, the combination 65 with a post-member having an annular recess, of a button-member comprising an oblong housing formed with a closed oval boss arranged with its major axis at a right angle to the major axis of the housing, an oblong 70 spring-carrying plate having an oblong opening registering with the entrance to the said boss, a spring mounted upon the said plate and having two arms arranged to normally extend across the ends of the entrance to the 75 said boss at a right angle to the major axis thereof, and an oblong assembling-plate adapted to have the housing fastened to it and formed with an opening for the passage 80 through it of the post-member for the access thereof to the interior of the boss through the opening in the spring-carrying plate.

7. In a curtain-fastener, the combination with a post-member having an annular recess the outer edge of which forms a guard 85 shoulder, of a button-member having an oblong opening for the reception of the said post-member, and a locking spring comprising two arms adapted to enter the said recess in the post-member and normally standing 90 across the ends of the oblong opening of the button-member at a right-angle to the major axis thereof whereby the pulling of the button-member in one direction or the other in line with the major axis of the said oblong 95 opening and substantially at a right angle to the axis of the said post-member, is a condition precedent to the removal of the button-member from the post-member.

In testimony whereof, I have signed this 100 specification in the presence of two subscribing witnesses.

JOHN KIRSCHBAUM.
